CLAIM

The ornamental design of a curved speaker face, as shown and described.

DESCRIPTION

FIG. 1 is a front perspective view of a curved speaker face, embodying our new design;

FIG. 2 is a front elevation view thereof;

FIG. 3 is a top plan view thereof; and,

FIG. 4 is a right side elevation view thereof, the left side elevation view being a mirror image thereto.

The broken lines shown are included for the purpose of illustrating portions of the curved speaker face that form no part of the claim.
